UNITED STATES PATENT OFFICE.

EDMUND OCUMPAUGH, OF ROCHESTER, NEW YORK, ASSIGNOR TO THE DEFIANCE MACHINE COMPANY, OF ROCHESTER, NEW YORK, A CORPORATION OF NEW YORK.

CHECK-WRITER.

1,162,388.

Specification of Letters Patent. Patented Nov. 30, 1915.

Application filed September 2, 1913. Serial No. 787,562.

To all whom it may concern:

Be it known that I, EDMUND OCUMPAUGH, a citizen of the United States, residing at Rochester, in the county of Monroe and 5 State of New York, have invented certain new and useful Improvements in Check-Writers, of which the following is a full, clear, concise, and exact description, reference being had to the accompanying drawings, forming a part of this specification.

My invention relates to an improved form of check-writing machine, in which suitable mechanism is provided for embossing or printing upon or into the check desired 15 amounts in dollars and cents, both in figures and in words. This result I accomplish by providing the mechanism with a single series of setting devices so that the proper manipulation of these setting devices simultaneously sets the two different printing mechanisms so that the proper amount will 20 be printed or embossed upon the check in both figures and words.

As is well known to those skilled in the 25 art, considerable difficulty is involved in constructing a device for printing any desired amount in words and correspondingly setting and printing the same amount in figures for the reason that the series of amounts expressed in words do not correspond with the 30 series of amounts expressed in figures; that is to say, while the amounts in the units column or the words expressing these amounts correspond from one to nine, inclusive, the next succeeding words for expressing 35 higher amounts correspond neither to higher values in the units series nor to the lower values in the tens series, for, as expressed in figures, the tens series is expressed 40 upon the second numeral wheel by means of the numerals "1" to "9" inclusive, which, when used, serve to indicate "10" to "90," dollars or cents, as the case may be. The 45 corresponding word series, however, must provide not only for expressing the words "ten" to "ninety" inclusive, but must provide for the intermediate words between ten and twenty, or "eleven" to "nineteen" inclusive, which words are naturally a combination 50 of the first figure of the second or tens order and the successive figures of the first or units order. It makes no difference, therefore, whether the intermediate words "eleven" to "nineteen" inclusive are regarded as a part of the tens series or as a

part of the units series; the difficulty of providing numerical printing devices to be actuated simultaneously with the word printing devices exists just the same for one relation as for the other since in any event it 60 means that for printing the words "eleven" to "nineteen" the tens and units printing wheels must both be operated so that the numeral "1" carried by the tens wheel must be brought into printing position and the 65 proper one of the numerals "1" to "9" of the units wheel must, at the same time, be brought into printing position, depending upon the particular one of the words which it is desired to print. The difficulty pointed out occurs every time that the words "eleven" to "nineteen" appear in the written portion of the check, whether in connection with the cents, the tens of dollars, tens of hundreds of dollars, the tens of 75 thousands of dollars, etc.

In carrying out my present invention I simplify the construction considerably by providing in the written portion of the check devices for indicating the fractional part of 80 a dollar, as is customarily done, instead of writing this fractional part out in cents, as may be done if desired. By my invention I also automatically provide means for printing the dollar sign immediately to the left 85 of the highest significant figure of the printed portion of the check, although normally zeros on the printing wheels are in the printing position so that any printing wheel which is not operated and is to the right of 90 an operated printing wheel will print a zero from the very fact that it has not been operated.

The mechanism for printing the written portion of the check is substantially that 95 shown in my issued Patent No. 843,410 and does not form of itself part of the present invention and is not claimed herein. Several features of improvement, however, are disclosed in the present application relating to 100 this printing mechanism as, for example, the devices employed for inking the type and these features of improvement, together with the devices simultaneously set up with the set-up of the written portion of the printing 105 mechanism for printing the numeral part of the check, together with the mechanism for controlling this numeral printing mechanism to at all times properly express the numeral amount, constitute the embodiment 110

of the present invention, which is particularly claimed herein. It will be understood that my invention consists, in addition to this, in the combination of the devices for writing the amount of a check in words and the devices referred to for printing the amount of the check in figures.

The several drawings illustrating my invention are as follows:

- 10 Figure 1 is a front elevation of the check-writing machine complete, with a portion of the casing broken away to more clearly disclose the interior mechanism of the machine. Certain of the parts are also broken 15 away, as will appear from the figure. Fig. 2 is a right-hand end view of the parts shown in Fig. 1, the end of the casing toward the observer being broken away to show the disposition of the parts within the 20 casing. Fig. 3 is a plan view of the printing devices shown in Figs. 1 and 2 with the inking and embossing mechanism, located in the upper part of the casing, removed, as is also the upper part of the casing referred 25 to. Fig. 4 is a sub-assembly view of the printing wheels used to print the numerical part of the check, together with the devices immediately associated with said wheels for actuating the same. Fig. 5 is a 30 longitudinal sectional view through the center of the shaft shown in Fig. 4. Fig. 6 is a view of the parts shown in Fig. 4 taken transversely of the shaft shown in said figure, along the lines 6—6. Fig. 7 is a similar 35 view of the parts shown in Fig. 4 taken along the line 7—7. Fig. 8 is a similar view of the parts shown in Fig. 4 taken along the line 8—8. Fig. 9 is an enlarged detail view of one of the printing slides 40 used to print the written part of the check, together with the mechanism directly connected therewith for setting said slide and for actuating the gearing used to set the corresponding devices shown in Fig. 4. Fig. 45 10 is a sectional view of the parts shown in Fig. 9, taken along the line 10—10. Fig. 11 is a top view of the parts shown in Figs. 9 and 10. Fig. 12 is a detail view of different positions assumed by the devices employed 50 to move the numeral wheels of higher order than the order of the highest numeral wheel set for printing an amount so that said higher order wheels are moved from their zero position before the printing operation. 55 Fig. 13 is a view of the parts shown in Fig. 12, taken along the line 13—13. Fig. 14 is a view of two of the operating levers and guards carried thereby, shown in Fig. 12, taken along the line 14—14, this view showing 60 the two levers in displaced position relatively to each other. Fig. 15 shows, in a view similar to Fig. 14, these operating levers in their normal or unoperated position. Fig. 16 is a top view of the bed plate 65 for receiving the check to be printed and

shows the opening therethrough by which the printing words and figures are brought into engagement with the check. Fig. 17 shows a sample check as printed or written by means of my check writer.

Similar numerals refer to similar parts throughout the several views.

As shown in Figs. 1, 2 and 3 the mechanism for printing or embossing the written part of the check consists of a plurality of 75 slides 1, 2, 3, 4 and 5 mounted side by side with their edges closely adjacent to each other so that they may be moved toward and away from the operator by means of the operating devices 6, 7, 8, 9 and 10 respectively, connected at their outer ends with the operating buttons 11, 12, 13, 14 and 15 respectively. The base 16 of the machine is provided with a smooth upper surface for supporting the slides 1 to 5 inclusive, and each slide is provided with a downwardly extending tongue, as indicated in Fig. 10, having ratchet teeth 18 formed in one side thereof to be engaged by a pawl 19 pivoted at 20 in a recess formed therefor in the upper surface of the top of the base 16 of the machine. The pawl 19 is provided with a pin 21 which extends downward through a notch 22 in a transverse controlling bar 23 and has secured to its lower 85 end a spring 24, the other end of which is secured to a stud 25 extending downward from the under surface of the top of the base of the machine. The tongue 17 has secured to its lower edge below the top of the 90 base of the machine a longitudinal bar 26, in which two parallel oblique slots 27 are formed, through which the retaining screws 28 pass which secure the strip to the tongue 17. The end of the strip 26, which is nearer 95 the observer, has a downwardly extending flange 29 formed thereon, in which a slot is formed engaged by a reduced section of a rod 30 extending through the operating tube 6. The rod 30, at its outer end, terminates 100 in an enlarged head or button 31, between which and the operating button 11, as indicated in Fig. 2, a spring 32 is located to maintain the rod 30 in its outermost position when it is not operated by pushing the 105 button 31 inward.

As a result of the construction described, when the button 31 is pushed inward the bar 26 is moved inward and, owing to the oblique relation of the slots 27, the bar is 110 moved to the left, as seen in Figs. 10 and 11, against the pin 21 to move the pawl 19 from engagement with the teeth 18, thus permitting a readjustment of the slide by means of the operating button 11, if for any reason 115 it is moved outward too far. The transverse bar 23 extends outside of the machine, as indicated in Fig. 1, and terminates in a releasing knob or button 33, which, when operated, releases all of the pawls 19 and

thus releases all of the printing slides and permits them to be returned to their initial position by means of suitable springs as follows: In the upper part 34 of the casing 5 a transverse shaft 35 is provided at the rear end, as indicated in Fig. 2, and upon this shaft a series of wheels 36 is mounted, one for each of the printing slides 1 to 5 inclusive. In the upper portion of the casing 34, 10 and near its front end, a second transverse shaft 37 is disposed, upon which a similar set of wheels 38 is mounted. Each of the wheels is freely rotatable upon its supporting shaft. Each of the wheels 38 contains 15 within it a spring 39, one end of which is secured to the shaft 37, the other end being secured to the wheel 38. Each wheel 38 has also secured to it one end of a flexible metal tape 40 which passes around the outer 20 surface of the wheel down toward the rear portion of the machine and around the corresponding wheel 36, the end of the tape being secured to the rear end of the corresponding printing slide. The parts are so 25 disposed that when the printing slide is in its initial or normal position, the spring 39 is under sufficient tension to positively hold it there and when the slide is drawn out to set up any desired amount, the tension on 30 the spring is somewhat increased so that when the slides are released the springs will at once return them to their normal position. The outer surfaces of the flexible strips or 35 tapes 40 are provided with numerals which may be made directly on the tapes' faces or secured thereto in any desired way, by which the setting of the corresponding slides may be observed through suitable sight openings 41 formed in the front wall of the upper 40 portion 34 of the casing of the machine. It is desirable to provide a resilient bumper 42 extending transversely of the machine at the rear end of the slides 1 to 5 inclusive, to absorb the shock incident to their stopping 45 when returned by the springs to their normal or initial position.

As indicated in Figs. 9 and 10, the tongue 17 has secured to its underside a rack 43, the points of connection being between the 50 ends of the rack and the ends of the tongue 17, so as to provide a clearance between the rack and tongue for containing the releasing mechanism above described. The racks referred to, connected with the slides 1 to 5 55 inclusive, engage gears 44 to 48 inclusive, mounted respectively upon transverse shafts 49 to 53 inclusive, indicated more clearly in the end view in Fig. 2. The engagement between each of the gears 44, 45, 46 and 48 60 with its corresponding driving rack is direct, whereas the engagement of the gear 47 with its driving rack is through an idler gear 47' connecting the gear 47 with its driving rack. The shaft 49 has secured to 65 its right-hand end, as shown in Fig. 2, a gear 54. The shaft 50 has secured to its right-hand end, as seen in Fig. 3, a gear 55. The shaft 51 has secured to its right-hand end, as shown in Fig. 3, the gear 56. The shaft 52 has secured to its right-hand end, 70 as shown in Figs. 2 and 3, a gear 57, and the shaft 53 has secured to its right-hand end, seen in Fig. 3, a gear 58. The gears 54 to 58 inclusive, engage and mesh with the gears 59 to 63 inclusive, shown more clearly in the 75 enlarged sub-assembly view seen in Fig. 4.

As indicated in Fig. 5, the gear 59 is rigidly secured to the right-hand end of a sleeve 64 to the left-hand end of which the numeral printing wheel 65 is rigidly secured. 80 The gear 60 is rigidly secured near the right-hand end of a slightly smaller sleeve 66, which is a free rotating fit within the sleeve 64, and said sleeve 66 has rigidly secured to its left-hand end the numeral 85 printing wheel 67. Within the sleeve 66 a third sleeve 68 is mounted, said sleeve 68 being of such a size as to be a free rotating fit in the sleeve 66, and this sleeve 68 has rigidly secured to its right-hand end a disk 90 69, between the hub of which and the extended right-hand end of the sleeve 66 the gear 61 is mounted so as to be freely supported upon the sleeve 68 so that it may turn relatively thereto unless prevented by 95 devices engaging it with the disk 69. The other end of the sleeve 68 has rigidly secured to it the numeral printing wheel 70. Within the sleeve 68 a fourth sleeve 71 is disposed, said sleeve 71 being of a size to rotate with 100 a free sliding fit in the sleeve 68, and this sleeve 71 has secured near its right-hand end a disk 72 similar to the disk 69. This sleeve has also secured to it, just to the left of the disk 72, a smaller disk 73, to the left of 105 which is mounted, concentric with the axis of the sleeve 71, a cam 74. The sleeve 71 has also secured thereto a second disk 75, similar to the disk 73, and between the disk 75 and the disk 69 a second cam 76 is mounted 110 around the sleeve 71, concentric with the axis of said sleeve. The gear 62 is mounted upon the sleeve 71 between the cam 74 and disk 75 so as to rotate freely upon said sleeve when not in any way secured to it by other 115 means. The other end of the sleeve 71 has rigidly secured to it the printing numeral wheel 77. A fifth sleeve 78 is disposed within the sleeve 71 so as to make a free rotating fit with said sleeve and the right-hand end 120 of this sleeve 78 has secured to it a disk 79, while its other end has secured to it a numeral printing wheel 80. The gear 63 is mounted upon the sleeve 78 between the hubs of the disks 72 and 79 so as to rotate 125 freely upon the sleeve 78 when not secured thereto by other devices. The sleeve 78 is rotatably supported upon a shaft 81 which constitutes a support for the whole of the numerical printing mechanism. 130

As a result of the construction described, it will be observed that when the printing slides 1 and 2 are adjusted to any desired values, the corresponding gears 59 and 60 are rotated and, therefore, that the numeral type wheels 65 and 67 are rotated. The slides 1 and 2 are preferably employed to indicate a fractional part of a dollar by printing it in fractional form and the printing wheels 65 and 67 carry similar numeral indications for printing the same amount in the numerical portion of the check as is set up by the slides 1 and 2 to be printed in the written portion of the check.

As pointed out above, the connection of the gears 61, 62 and 63 to the corresponding numeral printing wheels is not fixed or rigid, but depends upon the use of additional devices as follows: The gear 61, as indicated in Fig. 6, has pivoted thereto, at 82, a spring pawl 83, having a blunt V-shaped projection 84 engaging a correspondingly shaped notch in the edge of the disk 69. The disk 69 has pivotally supported thereon, at 85, a spring pawl 86 having a laterally extending pin 87 extending over the cam 76 and the disk 75 so that said pin may engage the notch 88 in the disk 75, indicated in Fig. 7, when said pin is rotated around to the right on the cam 76 a sufficient amount to pass from the larger diameter portion of the cam to its smaller diameter portion, the notch 88 being normally at the point of change from one diameter to the other.

The slide 3 is provided with two sets of words, the first being from "one" to "nine" inclusive and the second being from "ten" to "nineteen" inclusive. It will be observed that the two series are separated by an amount equal to the spacing of one word to another. The cam 76 is so constructed that when the slide 3 is moved to a position to bring one of the words "one" to "nine" into printing position, the pin 87 rests upon the larger portion of the cam, and during this adjustment the gear 61 drives the disk 69 by means of the spring pawl 83 and thus brings the corresponding numeral on the printing wheel 70 into printing position. The printing wheel 70 is also provided with a second set of figures following the first set just referred to from "0" to "9" inclusive, to be brought into printing position when the corresponding words "ten" to "nineteen" are brought into printing position by the slide 3. During the movement of the slide, however, to its position indicating the word "ten", the pin 87 passes from the portion of larger diameter of cam 76 to the portion of smaller diameter, thus engaging the slot 88 and from that point on causing rotation not only of the sleeve 68 and numeral printing wheel 70 connected therewith, but also causing rotation of the sleeve

71 and the numeral printing wheel 77 since the disk 75 is rigidly secured to said numeral wheel 77 by means of the sleeve 71. The numeral wheel 77 is provided around a portion of its circumference with a series of figures "1" so that for any position to which it may be moved throughout this series, the numeral "1" will be brought into printing position and it is this series of numerals on the numeral printing wheel 77 that is brought, one after the other, into printing position by the operation of the pin 87.

It will be noted that the direction of rotation from "0" position of the printing wheel 77 for the operation referred to is over and away from the observer at its top or upper portion when the slide 3 is being moved outward toward the operator. It will also be observed that the same direction of rotation is imparted to each of the numeral wheels 65, 67 and 70 when the slides 1, 2 and 3 move toward the operator. As indicated in Fig. 8, the gear 62 has pivotally secured thereto at 89, a spring pawl 90 provided with a laterally extending pin 91 which extends over the edge of the cam 74 and also over the edge of the disk 73. As a result, when the gear 62 is rotated toward the observer, as seen in Figs. 4 and 5, the pin 91 at once passes from the portion of larger diameter to the portion of smaller diameter of the cam 74 and engages the slot 92 formed in the edge of the disk 73, from which time continued rotation of the gear 62 rotates the sleeve 71 and, therefore, the printing wheels 77, but in a direction the reverse from that referred to above in describing the operation of the printing wheel 77 by means of the gear 61. It will be observed that the gear 62 is driven through an idler gear 47' instead of directly from the corresponding driving rack and in this manner an outward motion of the slide 4 rotates the gear 62 over toward the observer, as seen in Fig. 4, instead of over and away from the observer, as is the case of the gears 59, 60, 61 and 63 when operated by an outward motion of the corresponding slides. The numeral wheel 77 has disposed around its periphery, in addition to the series of figures "1", above referred to, a second series of figures "2" to "9" inclusive. The parts are so proportioned that an outward movement of the slide 4 brings this second set of figures into printing position corresponding to the one of the series of words "twenty" to "ninety" inclusive, carried by the printing slide 4.

From the description just given, it will be apparent that when the slide 3 is operated to bring one of the printing words "one" to "nine" inclusive, into printing position, the printing wheel 70 is rotated so as to bring the corresponding numeral into printing position; and further, that when

the slide 4 is operated to bring one of the words "twenty" to "ninety" into printing position, that the numeral printing wheel 77 is rotated, but in the reverse direction, 5 so as to bring the corresponding one of the numerals "2" to "9" into printing position. When, however, the slide 3 alone is moved to bring into printing position one of the words "ten" to "nineteen", the printing 10 wheel 70 is first rotated so as to successively bring into printing position the numerals corresponding to "1" to "9", inclusive, and that during the movement of the slide 3 from the last of its first series of printing 15 words to the beginning of the first of its second series of printing words into printing position, the numeral printing wheels 70 and 77 are locked together in such a manner that both are rotated in the same direction 20 so that continued motion of the slide 3 rotates the two printing wheels to bring the numerals "10" to "19" into printing position successively, depending upon which of the words "ten" to "nineteen" of the 25 slide 3 is brought into printing position.

From the above it will appear that the sleeve 71 and the printing wheel 77 secured thereto are normally disconnected from the gear 62, which must be the case in order to 30 permit the operation of the sleeve 71 either by the gear 62 or by the gear 61, according to whether the printing wheel 77 is actuated by the slide 4 or the slide 3. To prevent an accidental displacement of the sleeve 71 35 and parts carried thereby during its disconnected intervals, a spring pawl 94 is provided, which is pivotally supported at 95, in any suitable manner, from the base of the machine, and has a blunt V-shaped projection 40 engaging a corresponding notch in the edge of the disk 72 so as to normally hold the disk 72 and parts secured thereto against rotation, unless the rotating force is sufficient to disengage the pawl from its notch 45 in the disk. The engagement between the pawl and disk is not sufficient to offer any appreciable resistance to the operation of the sleeve 71 when either the gear 62 or the gear 61 is operated so as to engage sleeve 50 71 by means of the pin 91 or the pin 87.

The gear 63 is connected with the disk 79 by means of a spring pawl 93, as indicated in Fig. 4, in a manner identical with that shown and described for the connection of 55 the gear 61 to the disk 69, as a result of which motion of the slide 5 toward the operator causes the printing wheel 80 to rotate over away from the observer, as indicated in Fig. 4, to successively bring into printing 60 position one of the numerals "1" to "9" inclusive, corresponding to the one of the series of words "one hundred" to "nine hundred" inclusive, brought into printing position by the slide 5. Each of the significant figures of the printing wheel 80 has

preferably disposed in front or to the left of it the dollar sign as indicated in Fig. 4, so that for any printing position to which the printing wheel 80 may be moved, the dollar sign will be printed closely at the 70 left-hand side of the numeral to prevent tampering with this portion of the indicated value of the check.

Each of the slides 3, 4 and 5 is preferably provided at its normal or initial printing position with a series of stars or other arbitrary characters so that, if printed, the check would be imprinted or embossed with these stars or characters to prevent entering 75 an amount in the corresponding place on 80 the check. It will be understood that it is desirable, for the purpose of effecting the operation of the cams referred to, to have blank intervals at some points on the word slides and wherever this is desirable it is 85 preferable to employ similar stars or characters so that if, for any reason, it should be attempted to print a check at such blank space, it would not result in leaving a blank 90 in the written portion of the check. Similarly, protective characters of any desired 95 form may be used upon the type wheels when for any reason, it is desirable to use delay blanks upon their surfaces. It is preferable, however, to provide against the possibility 100 of a printing operation at the blank places on the slides by removing the corresponding teeth on the ratchets 18 or by providing locking mechanism for operating with the slides so that it is impossible to actuate the 105 printing devices unless the printing slides are in their proper printing positions. This can readily be accomplished by providing a series of notches in the edges of the printing slides 1 to 5 inclusive, which must be 110 engaged by projections secured to or co-operating with a rack held in the path of the printing lever, or parts carried thereby, unless the projections enter notches in all of the printing slides.

The upper portion 34 of the casing of the machine has mounted, in its forward portion, a transverse shaft 95, below the shaft 37, and to the right-hand end of this shaft 95, as seen in Fig. 1, a printing lever 96 is 115 secured. The casing 34 is supported by upwardly extending brackets 97 and 98 secured to the base of the machine, as indicated, which brackets constitute the end support for the shafts 35, 37 and 95. The 120 brackets 97 and 98 also have extending between them a transverse shaft 99, upon which the rear ends of the curved levers 100 are pivotally supported. The forward ends of these levers 100 support a platen 101 provided on its lower edge with a strip of resilient material 102 over the printing opening 103 formed in the bed plate 104. The bed plate 104 is hinged at its forward edge 125 at 105 to the base of the machine and is nor- 130

mally held in its upper position by a spring 106. Hook gages 107 are provided, as indicated in Figs. 2 and 16, for determining the position of the check to be printed or embossed, and these hook gages have secured to their forward ends the clamping thumb screws 108, by means of which the gages may be adjusted as desired in the slots 109. The platen 101 is provided near either end upon its upper surface with a roller 110, which is engaged by a cam 111 rigidly secured to the printing shaft 95. The printing shaft 95 has also secured to it two curved levers 112, between the lower ends of which the inking rollers 113 and 114 are disposed. The bed plate 105 in its normal position is sufficiently above the printing slides and printing type wheels to permit the printing rollers 113 and 114 to rest between and in front of the printing positions of the printing slides and type wheels and the bed plate 104. When the printing lever 96 is operated by moving it toward the observer, in Fig. 1, or around to the left, as indicated in Fig. 2, to the dotted position, the inking rollers 113 and 114 are first moved across the type which have been brought into printing position and when the inking rollers are clear of the bed plate 104 the cams 111 move the platen 101 downward against the check resting upon the bed plate 104, from which time the check, bed plate and platen move together to bring the check into contact with the printing words and figures which have been brought into printing position, with the result that the check is written something as indicated in Fig. 17, assuming the set-up of the machine to have been as indicated in Fig. 16. In Fig. 17 the check is designated by the numeral 160, and the written and printed portions of the check are shown at 161 and 162, respectively. At about the end of the printing stroke the inking rollers 113 and 114 are brought into engagement with a supply ink roller 115, by which the rollers 113 and 114 are kept in properly inked condition. A spring 116 is provided for returning the shaft 95, and parts carried thereby, to their initial position and a spring 117 is provided for moving the platen 101 to its upper position when released from the cams 111. The platen 101 is provided at either end with a spring actuated roller 118 which rests upon the check and holds the same in position until the platen is brought nearly or quite into engagement with the printing characters. This avoids the displacement of the check upon the bed plate which might otherwise occur.

I have found it desirable, in connection with the numeral printing wheels, to place the dollar sign immediately to the left of the highest numeral wheel actuated so that the amount printed by the numeral wheels

may in every case be free from zeros to the left of the highest significant figure. This I accomplish by the following construction: The top of the base 16 has secured to it in front of the gears 62 and 63 a downwardly extending bracket 119 which supports each of three actuating levers, 120, 121 and 122 in a corresponding vertical slot by means of two transverse pins 123 and 124, which are supported in parallel oblique slots 125 and 126. Each of these levers is provided at its rear end with a laterally extending pin 127 which is disposed opposite a slot or notch 128 formed in the edge of the corresponding one of the disks 69, 72 and 79; that is to say, the rear end of the lever 120 is disposed adjacent to the periphery of the disk 79, the rear end of the lever 121 is disposed adjacent to the periphery of the disk 72 and the rear end of the lever 122 is disposed adjacent to the periphery of the disk 69, so that each lever, under conditions to be described, may actuate the corresponding disk. The forward end of each one of these levers is pivotally connected, as indicated for lever 120 in Fig. 2, with the upper end of a link 129, the lower end of which is pivotally connected with a horizontal arm of the bell crank lever 130 pivotally supported upon a shaft 131. The shorter and vertical arm of the bell crank lever 130 is connected by a link 132 with a vertically extending crank 133 by a pin and slot connection, the pin being maintained in the left-hand end of the slot by a spring 134 extending between the upper end of the lever 133 and a bracket secured to the link 132. The cranks 133 are rigidly secured to a shaft 135 which has also rigidly secured thereto an operating lever 136 pivotally connected by a link 137 with a crank 138 pivotally supported at 139 from the bracket 98. The crank 138 has secured thereto a bent upwardly extending lever 140, carrying at its upper end a roller 141 adapted to be engaged by a cam 142 rigidly secured upon the printing shaft 95. The crank 138 is engaged by a spring 143 for maintaining the roller 141 against the cam 142 and also maintaining the parts rigidly connected with the crank 138 in their normal position when the printing lever 96 is in the position indicated in Fig. 2. Each of the links 129 is pivotally connected between its ends by means of a link 144 with a crank 145 by a pin and slot connection, the pin being held in the left-hand end of its slot by means of a spring 146 extending between the upper end of the crank 145 and a bracket secured to the link 144. The cranks 145 are rigidly secured to a transverse shaft 147, to which is also secured an operating crank 148 pivotally connected by a link 149 with the crank 138. As a result of the construction described it will be observed that

when the printing lever 96 is rotated around to the left, as seen in Fig. 2, before the cams 111 engage the rollers 110, the lever 140 will be engaged by the cam 142 and moved to its dotted position, thus placing the springs 134 and 146 under tension, if motion of the levers 120, 121 and 122 is prevented. If, however, the pin at the rear end of one of these levers is in alignment with a slot 128 in its corresponding disk, said lever will first be moved rearwardly in the slots 125 and 126 until the pin 124 passes into the enlarged portion of the slot 126 under the action of the spring 146, at which time the tension exerted upon the spring 134, by the movement of the pin in the crank 133 to the right in its slot, is released and the bell crank lever 130 moves the forward end of said lever upward and the rear end downward, the pin 123 at this time serves as a pivot about which the lever rotates to rotate the corresponding disk a similar amount. From the description just given, it will appear that when one of the disks 69, 72 and 79 has been moved from its initial or normal position by the operation of the corresponding slides, the corresponding one of the levers 120, 121, and 122 cannot be displaced from the position indicated in Fig. 2 for the reason that the pin 127 will rest upon the circumference of the disks out of alignment with the slot 128. Any of the levers, however, having its pin 127 in alignment with the slot 128 in the corresponding disk will be actuated during the first portion of the printing operation in the manner described above, not positively but through the medium of the springs 146 and 134.

By referring particularly to Figs. 12 and 13, the operation of the levers 120, 121 and 122 will be best understood, as well as the results secured by the operation. As shown in Fig. 12, the lever 122 is assumed to be prevented from operation by the fact that its disk 69 has been actuated by the corresponding printing slide. The levers 121 and 120 are shown in actuated position permitted by the fact that at the beginning of the printing operation their disks 72 and 79 respectively, had their slots or notches 128 in alignment with the pins 127.

Interlocking devices are carried by the levers 120, 121 and 122 for limiting the amount of motion of these levers relative to each other as follows: The levers 121 and 122 carry U-shaped members 150 and 151. The member 150 is secured to the lever 121 in such a manner that its projecting legs extend above and below the lever 120 with sufficient clearance so that the relative motion of the lever 120 relatively to the lever 121, or vice versa, is sufficient to move the corresponding disk and connected printing wheel the space of one character on the periphery of said printing wheel. The member 151 is similarly connected to the lever 122 so as to permit the same amount of relative motion of the levers 121 and 122. In normal or initial position, each of the levers 120 and 121 is in contact, or substantially so, with the lower leg of the corresponding one of the members 150 and 151. As a result of this construction, it will appear that if the three dollar printing wheels 70, 77 and 80 have been moved from their zero position by the setting of the corresponding printing slides, that none of the levers 120, 121 and 122 can be actuated from its normal or initial position shown in Fig. 2; if only the units and tens of dollars printing wheels 70 and 77 are operated and the hundreds printing wheel is not operated, the lever 120 is operated, as above described, by the printing operation and its motion is limited by member 150 to the space of one character of the printing wheel 80 since the levers 121 and 122 can not be moved from the position indicated in Fig. 2, owing to the fact that the slots 128 have been moved from under the pins 127; the same result occurs if only the tens of dollars printing wheel 77 is operated for by this operation the disk 72 is moved to a position to prevent operation of the lever 121 and, therefore, the lever 120 can only move an amount corresponding to one character of the printing wheel 80 and the lever 122 cannot be moved even though the slot 128 is in alignment with the pin 127 on the lever 122, for the reason that the member 151 carried by the lever 122 engages the lower edge of the lever 121 which prevents upward movement of said member 151, and, therefore, prevents operation of the lever 122; when the units of dollars printing wheel 70 is the only one of the dollars printing wheels which is actuated, the lever 122 is retained in its normal or initial position for the reasons mentioned above and the levers 121 and 120 are operated as far as the members 151 and 150 will permit them to be moved, or, in other words the lever 121 is moved an amount sufficient to rotate the tens of dollars printing wheel 77 one step and the lever 120 is moved an amount sufficient to rotate the hundreds of dollars printing wheel 80 two steps, since it may move one step relatively to the member 150 and the member 150 may move one step relatively to the member 151. It will be observed that the motion imparted to the printing wheels by the operation of the levers 120, 121 and 122 is always in a direction the reverse of the sequence of the figures on the numeral wheels, with the exception of the printing wheel 77, in which case it is in the same direction as the sequence of the numerals "2" to "9" inclusive. Each of the numeral wheels 70, 77 and 80 carries, in line with its printing numerals, a zero

which normally rests in the printing position and one step below the zero on each of the wheels 70 and 80 a dollar sign is carried, below which there is left in the next space a blank. On the printing wheel 77 the first step from the zero in the direction of the sequence of figures carried by said wheel, a dollar sign is carried and the next step upon this printing wheel is left blank. In other words, the dollar signs carried by the printing wheels 70, 77 and 80 are, in each case, immediately above the zeros carried by said wheels, as indicated in Fig. 3, and the spaces immediately above the dollar signs are left blank.

The enlargements at the right-hand end of the slots 126 shown in Figs. 2 and 12 are so conformed as to limit the motion of the pins 124 so that the corresponding levers 120, 121 and 122 cannot, in any event be moved angularly a sufficient distance to move the printing wheels more than two spaces so that any possibility of bringing the printing numerals adjacent to the blank spaces on the printing wheels into printing position by levers 120, 121 and 122 is avoided.

As already pointed out, the operation of the levers 120, 121 and 122 is such as to rotate the printing wheels actuated thereby over toward the observer for the position seen in Fig. 3, and, therefore, any printing wheel which is moved one step by the operation of the corresponding lever will have its zero moved from printing position and its dollar sign moved into printing position, and any printing wheel which is moved two steps will have its zero moved from printing position and its dollar sign moved through the printing position so as to permit the blank on the other side of the dollar sign to be brought into printing position.

As a result of the construction described, it will be understood that if no one of the slides 3, 4 and 5 is actuated and if the slides 1 and 2 are operated in a manner to indicate any desired number of cents as a fractional part of a dollar, as, for example, 10¢, the impression made by the slides upon the written portion of the check will be as follows:

*****and 10/100 dollars

the word dollars being printed in each case upon the check and not printed by the check-writing machine, although if desired a rigid type block might be carried by the base 16 to print this word each time, if preferred, and at the same time the printing wheel 67 is moved to bring the "1" to printing position, the printing wheel 70 is moved backward to bring the dollar sign into printing position and the wheels 77 and 80 are moved two steps in the same direction as the printing wheel 70, which brings the

blank spaces carried by them into printing position and, therefore, the value printed by the numeral wheels will read as follows:

\$10/100

70

Similarly if the slide 3 is actuated to bring the word "one" into printing position without moving the other slides, the printing wheel 70 is moved to bring the numeral "1" into printing position and the amount printed in words on the check will appear as follows:

*****one and 00/100 dollars

and the amount printed by the numeral wheels will read

\$1 00/100

Similarly if the slide 4 is moved to bring the word "twenty" into printing position without operating any of the other slides, the amount printed in words will appear as follows:

*****twenty***** and 00/100 dollars

90

and the amount printed by the numeral wheel will read:

\$20 00/100.

Similarly, if the slide 5 is moved to a position to bring the words "one hundred" into printing position without moving the other slides, the amount printed in words will appear as follows:

***** hundred *** and 00/100

100

and the amount printed in figures will appear as follows:

\$100 00/100.

105

It will be understood that while I have shown but three slides, to-wit, 3, 4 and 5, for printing dollars, that as many such slides may be employed as desired and that as often as it is necessary or desirable to employ in connection with the units series "one" to "nine" the second series "ten" to "nineteen," the same apparatus is employed to be operated by the slide bearing such two series of words, so that one or both of two adjacent printing wheels are operated corresponding to the two orders of units represented by the words carried by said slide, and the next higher slide, in such event, will preferably carry a series of words corresponding to a continuation of the second series of words carried by the first slide, so that the printing wheel of higher order may be operated by said second slide in substantially the manner described for the operation of the printing wheel 77 by the slide 4. In this manner wherever the series of words "ten" to "nineteen" appears there is preferably employed a combination of two slides carrying printed

110

115

120

125

130

words in different series, each slide having its own printing wheel, while for certain of the indications, one of the slides operates both printing wheels. Furthermore, it will 5 be understood that the devices employed for placing the dollar sign immediately to the left of the highest order numeral brought into printing position by the printing wheels may be extended to any number of orders.

10 While I have referred repeatedly in the present specification and claims to the operation of the mechanism as "printing" I desire to have it understood that by this term I include any form of imprinting or embossing the characters into or through the 15 paper, whether the fiber of the paper is torn or cut by the printing operation or not. In this printing operation it is preferable to employ indelible ink so that the ink may be 20 carried into the fiber of the paper by the printing operation and thus render it practically impossible to eliminate the ink from the paper. The check writer, therefore, constitutes also a check protector.

25 It will be noted that the supply ink roll 115 is mounted upon crank arms and that the shaft of the said supply inking roll is extended through the side walls of the upper portion of the casing of the machine and 30 terminates in the knobs 115^a. This is for the purpose of moving the supply inking roll 115 out of the path of the inking rollers 113 and 114 when desired.

35 It will be understood that while I have shown my invention in the particular embodiments herein described, I do not, however, limit myself to these exact constructions, as I may employ many equivalents for securing the results herein illustrated and 40 described.

What I claim is:

1. In a check-writing machine, the combination of a first set of ordered printing devices for printing the written portion of a check, mechanism for setting said devices to print a desired amount, a second set of printing devices for printing the numerical part of the check, gearing connecting corresponding ones of the two sets of devices, 45 the second set of devices each having a normally in printing position, an actuating member, and mechanism actuated by said member for moving the printing devices of the second set of higher order than the highest 50 actuated one of the second set of devices to move the corresponding zeros from the printing position.

2. In a check-writing machine, the combination of a first set of ordered printing devices for printing the written portion of a check, mechanism for setting said devices to print a desired amount, a second set of printing devices for printing the numerical part of the check, gearing connecting corre-

sponding ones of the two sets of devices, 65 each of said second set of printing devices having printing characters in sequence from 0 to 9 inclusive, the zero being normally in printing position, the devices of the second set also being provided on the other side of 70 the zero characters with arbitrary characters not indicating quantity, an actuating member, and mechanism operated by the actuating member for moving the device of the second set of the next higher order than the 75 highest actuated device of said second set to move its zero character from printing position and bring said arbitrary character into printing position.

3. In a check-writing machine, the combination of a first set of ordered printing devices for printing the written portion of a check, mechanism for setting said devices to print a desired amount, a second set of printing devices for printing the numerical 80 part of the check, gearing connecting corresponding ones of the two sets of devices, each of said second set of printing devices having printing characters in sequence from 0 to 9 inclusive, the zero being normally in 85 printing position, the devices of the second set also being provided on the other side of the zero characters with arbitrary characters not indicating quantity, an actuating member, and mechanism actuated by the actuating member for moving the devices of the second set of higher order than the highest 90 actuated device of said set to move the zero of the device of next higher order from printing position and bring the corresponding 95 arbitrary character in position and also to move the other higher ordered devices a greater amount in the same direction to bring blank spaces on said devices into printing position. 100

4. In a check-writing machine, the combination of a first set of ordered printing devices for printing the written portion of a check, mechanism for setting said devices to print a desired amount, a second set of printing devices for printing the numerical part of the check, gearing connecting corresponding ones of the two sets of devices, each of said second set of printing devices having a set of printing characters from 0 105 to 9 inclusive, a dollar sign in the next space back of the zero, and a blank space back of the dollar sign, an actuating member, and mechanism actuated by the actuating member for moving the devices of the second set 110 of higher order than the device of highest order actuated to bring the dollar sign on the device of next higher order into printing position and to bring the blank spaces on the higher ordered devices into printing 115 position. 120

5. In a check-writing machine, the combination of a first set of ordered printing

devices for printing the written portion of a check, mechanism for setting said devices to print a desired amount, a second set of printing devices for printing the numerical part of the check, gearing connecting corresponding ones of the two sets of devices, each of said second set of printing devices having a set of printing characters from 0 to 9 inclusive, a dollar sign in the next space 5 back of the zero, and a blank space back of the dollar sign, an actuating member, and mechanism actuated by the actuating member for bringing the dollar sign on the device of the second set of next higher order 10 to the highest device actuated into printing 15 position by the printing operation.

6. In a check-writing machine, the combination of a first set of ordered printing devices for printing the written portion of 20 a check, mechanism for setting said devices to print a desired amount, a second set of printing devices for printing the numerical part of the check, gearing connecting corresponding ones of the two sets of devices, 25 each of said second set of printing devices having a set of printing characters from 0 to 9 inclusive, a dollar sign in the next space back of the zero, and a blank space back of the dollar sign, an actuating member, and 30 mechanism actuated by the actuating member for bringing the dollar sign on the device of the second set of next higher order to the highest device actuated into printing position by the printing operation, and locking 35 devices for preventing the displacement of one of the devices of the second set from its normal position when it is not operated and it is lower than the device of the highest order that is operated, said locking 40 devices being inoperative when the same device of the second set is of higher order than the highest ordered device of the second set that is operated.

7. In a check-writing machine, the combination of a first set of ordered printing devices for printing the written portion of a check, mechanism for setting said devices to print a desired amount, a second set of printing devices for printing the numerical part of the check, gearing connecting corresponding ones of the two sets of devices, each of said second set of printing devices having a set of printing characters from 0 to 9 inclusive, a dollar sign in the next space 50 back of the zero, and a blank space back of the dollar sign, an actuating member, mechanism actuated by the actuating member for bringing the dollar sign on the device of the second set of next higher order to the 55 highest device actuated into printing position by the printing operation, and mechanism for simultaneously returning the printing devices to their zero position.

8. In a check writer, the combination of 60 a set of ordered slides bearing characters for

printing the written part of a check, a set of ordered printing wheels bearing characters for printing the numerical part of a check, gearing for actuating the printing wheels from the corresponding ones of the 70 slides, one of said slides carrying two series of characters or words, one series belonging to one order and the other series including the same order and the next higher order, and mechanism controlled by the operation 75 of said slide for operating the wheel of the order corresponding to the first series when one of said series is brought into printing position and for controlling the operation of the same printing wheel and the printing 80 wheel of next higher order when said slide is moved to bring one of said second series into printing position.

9. In a check writer, the combination of 85 a set of ordered slides bearing characters for printing the written part of a check, a set of ordered printing wheels bearing characters for printing the numerical part of a check, gearing for actuating the printing wheels from the corresponding ones of the 90 slides, one of said slides carrying two series of characters or words, one series belonging to one order and the other series including the same order and the next higher order, and mechanism controlled by the operation 95 of said slide for operating the wheel of the order corresponding to the first series when one of said series is brought into printing position and for controlling the operation of the same printing wheel and the printing 100 wheel of next higher order when said slide is moved to bring one of said second series into printing position without interfering with the subsequent operation by the slide of next higher order of the printing wheel 105 of higher order actuated by the slide of lower order.

10. In a check writer, the combination of 110 a set of ordered slides bearing characters for printing the written part of a check, a set of ordered printing wheels bearing characters for printing the numerical part of a check, gearing for actuating the printing wheels from the corresponding ones of the 115 slides, one of said slides carrying two series of characters or words, one series belonging to one order and the other series including the same order and the next higher order, and mechanism controlled by the operation 120 of said slide for operating the wheel of the order corresponding to the first series when one of said series is brought into printing position and for controlling the operation of the same printing wheel and the printing wheel of next higher order when said slide is moved to bring one of said second series into printing position, each printing wheel having printing characters from 0 to 9 and disposed with the 125 zero normally in printing position and hav-

ing also a dollar sign in the next space back of the zero and a blank space back of said dollar sign, a printing lever, and mechanism actuated by the printing lever for moving the printing wheel of next higher order to the one of highest order actuated to bring the dollar sign into printing position.

11. In a check writer, the combination of a set of ordered slides bearing characters for printing the written part of a check, a set of ordered printing wheels bearing characters for printing the numerical part of a check, gearing for actuating the printing wheels from the corresponding ones of the slides, one of said slides carrying two series of characters or words, one series belonging to one order and the other series including the same order and the next higher order, and mechanism controlled by the operation of said slide for operating the wheel of the order corresponding to the first series when one of said series is brought into printing position and for controlling the operation of the same printing wheel and the printing wheel of next higher order when said slide is moved to bring one of said second series into printing position, each printing wheel having printing characters from 0 to 9 and disposed with the zero normally in printing position and having also a dollar sign in the next space back of the zero and a blank space back of said dollar sign, a printing lever, and mechanism actuated by the printing lever for moving the printing wheel of next higher order to the one of highest order actuated to bring the dollar sign into printing position and for moving the printing wheels of still higher order to bring the blank spaces into printing position.

12. In a check writer, the combination of a set of ordered slides bearing characters for printing the written part of a check, a set of ordered printing wheels bearing characters for printing the numerical part of a check, gearing for actuating the printing wheels from the corresponding ones of the slides, one of said slides carrying two series of characters or words, one series belonging to one order and the other series including the same order and the next higher order, mechanism controlled by the operation of said slide for operating the wheel of the order corresponding to the first series when one of said series is brought into printing position and for controlling the operation of the same printing wheel and the printing wheel of next higher order when said slide is moved to bring one of said second series into printing position without interfering with the subsequent operation by the slide of next higher order of the printing wheel of higher order actuated by the slide of lower order, devices for holding the slides in their set position for printing a desired amount, and mechanism for permitting the

individual adjustment of any slide and the gearing and printing wheel connected therewith.

13. In a check writer, the combination of a set of ordered slides bearing characters for printing the written part of a check, a set of ordered printing wheels bearing characters for printing the numerical part of a check, gearing for actuating the printing wheels from the corresponding ones of the slides, one of said slides carrying two series of characters or words, one series belonging to one order and the other series including the same order and the next higher order, mechanism controlled by the operation of said slide for operating the wheel of the order corresponding to the first series when one of said series is brought into printing position and for controlling the operation of the same printing wheel and the printing wheel of next higher order when said slide is moved to bring one of said second series into printing position, each printing wheel having printing characters from 0 to 9 and disposed with the zero normally in printing position and having also a dollar sign in the next space back of the zero and a blank space back of said dollar sign, a printing lever, mechanism actuated by the printing lever for moving the printing wheel of next higher order to the one of highest order actuated to bring the dollar sign into printing position and for moving the printing wheels of still higher order to bring the blank spaces into printing position, devices for holding the slides in their set position for printing a desired amount, and mechanism for permitting the individual adjustment of any slide and the printing wheel and gearing connected therewith.

14. In a check writer, the combination of a set of ordered slides bearing characters for printing the written part of a check, a set of ordered printing wheels bearing characters for printing the numerical part of a check, gearing for actuating the printing wheels from the corresponding ones of the slides, one of said slides carrying two series of characters or words, one series belonging to one order and the other series including the same order and the next higher order, mechanism controlled by the operation of said slide for operating the wheel of the order corresponding to the first series when one of said series is brought into printing position and for controlling the operation of the same printing wheel and the printing wheel of next higher order when said slide is moved to bring one of said second series into printing position without interfering with the subsequent operation by the slide of next higher order of the printing wheel of higher order actuated by the slide of lower order, devices for holding the slides in set position for printing a desired amount, and mechanism for permitting the

amount, and mechanism for returning the slides and the gearing and printing wheels connected therewith to their zero or normal position.

- 5 15. In a check writer, the combination of a set of ordered slides bearing characters for printing the written part of a check, a set of ordered printing wheels bearing characters for printing the numerical part of a
 10 check, gearing for actuating the printing wheels from the corresponding ones of the slides, one of said slides carrying two series of characters or words, one series belonging to one order and the other series including
 15 the same order and the next higher order, mechanism controlled by the operation of said slide for operating the wheel of the order corresponding to the first series when one of said series is brought into printing
 20 position and for controlling the operation of the same printing wheel and the printing wheel of next higher order when said slide is moved to bring one of said second series into printing position, each printing
 25 wheel having printing characters from 0 to 9 and disposed with the zero normally in printing position and having also a dollar sign in the next space back of the zero and a blank space back of said dollar sign, a
 30 printing lever, mechanism actuated by the printing lever for moving the printing wheel of next higher order to the one of highest order actuated to bring the dollar sign into printing position and for moving the printing
 35 wheels of still higher order to bring the blank spaces into printing position, devices for holding any of said slides in set position for printing a desired amount, and mechanism for returning the slides and the gear-
 40 ing and printing wheels connected therewith to their zero or normal position.
16. In a check-writing machine, the combination of a plurality of ordered slides carrying words for printing desired amounts
 45 on the written portion of a check, a first one of said slides bearing characters for printing a first series of words, "One" to "Nine" inclusive and characters for printing a second series of words "Ten" to "Nineteen" in-
 50 clusive, a second slide of next higher order having characters for printing the words "Twenty" to "Ninety" inclusive, devices for bringing desired ones of the words into printing position, a set of ordered printing
 55 wheels, one for each of the slides, gearing between said first slide and a first one of said printing wheels of corresponding order, gearing between said second slide and a second one of said printing wheels of next
 60 higher order, said first printing wheel carrying two sets of printing figures, each being from 0 to 9 inclusive, the second printing wheel carrying two sets of printing figures, one being from 0 to 9 inclusive with the omis-

sion of the numeral 1, and the other being a plurality of numerals 1, and mechanism operating to bring one of the first series of printing figures on said first wheel into printing position when one of the first series of words on the first slide is brought into printing position and to bring one of the second series of printing figures on said first wheel and one of said second series of printing figures on said second wheel into printing position when said first slide is moved to a position to bring one of its second series of words into printing position.

17. In a check-writing machine, the combination of a plurality of ordered slides carrying words for printing desired amounts on the written portion of a check, a first one of said slides bearing characters for printing a first series of words, "One" to "Nine" inclusive and characters for printing a second series of words "Ten" to "Nineteen" inclusive, a second slide of next higher order having characters for printing the words "Twenty" to "Ninety" inclusive, devices for bringing desired ones of the words into printing position, a set of ordered printing wheels, one for each of the slides, gearing between said first slide and a first one of said printing wheels of corresponding order, gearing between said second slide and a second one of said printing wheels of next higher order, said first printing wheel carrying two sets of printing figures, each being from 0 to 9 inclusive, the second printing wheel carrying two sets of printing figures, one being from 0 to 9 inclusive with the omission of the numeral 1, and the other being a plurality of numerals 1, and mechanism operating to bring one of the first series of printing figures on said first wheel into printing position when one of the first series of words on the first slide is brought into printing position and to bring one of the second series of printing figures on said first wheel and one of said second series of printing figures on said second wheel into printing position when said first slide is moved to a position to bring one of its second series of words into printing position, the subsequent operation of the second slide operating the second wheel to bring one of its first series of printing figures into printing position.

18. In a check-writing machine, the combination of a plurality of ordered slides carrying words for printing desired amounts on the written portion of a check, a first one of said slides bearing characters for printing a first series of words "One" to "Nine" inclusive and characters for printing a second series of words "Ten" to "Nineteen" inclusive, a second slide of next higher order having characters for printing the words "Twenty" to "Ninety" inclusive,

- devices for bringing desired ones of the words into printing position, a set of ordered printing wheels, one for each of the slides, gearing between said first slide and a 5 first one of said printing wheels of corresponding order, gearing between said second slide and a second one of said printing wheels of next higher order, said first printing wheel carrying two sets of printing figures, each being from 0 to 9 inclusive, the 10 second printing wheel carrying two sets of printing figures, one being from 0 to 9 inclusive with the omission of the numeral 1, and the other being a plurality of numerals 15 1, a first cam for connecting the gearing between said second slide and said second printing wheel in operative relation when said second slide is operated, and a second cam for connecting the gearing between said 20 first slide and said second wheel in operative relation when said first slide is actuated to bring one of its second series of words into printing position.
19. In a check-writing machine, the combination of a plurality of ordered slides carrying words for printing desired amounts on the written portion of a check, a first one of said slides bearing characters for printing a first series of words "One" to 25 "Nine" inclusive and characters for printing a second series of words "Ten" to "Nineteen" inclusive, a second slide of next higher order having characters for printing the words "Twenty" to "Ninety" inclusive, 30 devices for bringing desired ones of the words into printing position, a set of ordered printing wheels, one for each of the slides, gearing between said first slide and a first one of said printing wheels of corresponding order, gearing between said second slide and a second one of said printing wheels of next higher order, said first printing wheel carrying two sets of printing figures, each being from 0 to 9 inclusive, the 35 second printing wheel carrying two sets of printing figures, one being from 0 to 9 inclusive with the omission of the numeral 1, and the other being a plurality of numerals 1, a first cam for connecting the gearing between said second slide and said second printing wheel in operative relation when said second slide is operated, and a second cam for connecting the gearing between said first slide and said second wheel in operative 40 relation when said first slide is actuated to bring one of its second series of words into printing position, the direction of rotation of said second wheel for actuation by one slide being opposite to its direction of rotation for actuation by the other slide.
20. In a check-writing machine, a first set of ordered printing devices for printing the written part of a check, one of said printing devices having characters for printing the 45 words "One" to "Nineteen" inclusive, a second set of ordered printing devices for printing the numerical part of a check and each carrying a series of printing figures beginning with 0 and ending with 9, and mechanism connecting the two sets of devices so that operation of said one of the first set of devices operates the corresponding one of the second set of devices when any one of the words "One" to "Nine" inclusive is brought into printing position, and so that it operates the same device of the second set and also the device of the second set of next higher order when any one of the words "Ten" to "Nineteen" is brought into printing position.
21. In a check-writing machine, a first set of ordered printing devices for printing the written part of a check, one of said printing devices having characters for printing the words "One" to "Nineteen" inclusive, 50 a second set of ordered printing devices for printing the numerical part of a check and each carrying a series of printing figures beginning with 0 and ending with 9, mechanism connecting the two sets of devices so that operation of said one of the first set of devices operates the corresponding one of the second set of devices when any one of the words "One" to "Nine" inclusive is brought into printing position, and so that it operates the same device of the second set and also the device of the second set of next higher order when any one of the words "Ten" to "Nineteen" is brought into printing position, and mechanism for operating said printing device of next higher order of the second set when the printing device of the first set of next higher order is actuated.
22. In a check-writing machine, the combination of a set of ordered printing devices, mechanism for setting said devices to print a desired amount, each of said printing devices carrying a series of printing characters and an arbitrary character back of the character of said series of lowest value, the lowest value characters being normally in printing position, an actuating member, and mechanism operated by the actuating member for moving the printing device of next higher order than the highest one operated in a backward direction to bring its said arbitrary character into printing position.
23. In a check-writing machine, the combination of a set of ordered printing devices, mechanism for setting said devices to print a desired amount, each of said printing devices carrying a series of printing characters and an arbitrary character back of the character of said series of lowest value, the lowest value characters being normally in printing position, an actuating member, and mechanism operated by the actuating mem-

- ber for moving the printing device of next higher order than the highest one operated in a backward direction to bring its said arbitrary character into printing position and for moving the printing devices of still higher order a further amount in a backward direction to bring blank spaces back of said arbitrary characters into printing position.
24. In a check-writing machine, the combination of a set of ordered printing devices, mechanism for setting said devices to print a desired amount, each of said printing devices carrying a series of printing characters and an arbitrary character back of the character of said series of lowest value, the lowest value characters being normally in printing position, an actuating member, mechanism operated by the actuating member for moving the printing device of next higher order than the highest one operated in a backward direction to bring its said arbitrary character into printing position, and locking mechanism for preventing the displacement from printing position of the character of lowest value on an unoperated printing device of lower order than the printing device of highest order operated.
25. In a check-writing machine, the combination of a set of ordered printing devices, mechanism for setting said devices to print a desired amount, each of said printing devices carrying a series of printing characters and an arbitrary character back of the character of said series of lowest value, the lowest value characters being normally in printing position, an actuating member, each of said printing devices having mechanism actuated by the actuating member for throwing said printing device out of its normal position when it has not been operated in setting up a desired amount, and devices for preventing movement of the printing devices of lower order than the highest ordered printing device actuated from their normal position by the operation of the printing member without interfering with said movement of the printing devices of higher order than the highest order of printing device actuated.
26. In a check writing machine, the combination of printing devices having digital indications in printing position, mechanism for setting said devices to print a desired amount, an actuating member for making a record from said devices, and mechanism for moving the digital indication of a printing device of higher value than the set up from printing position.
27. In a check-writing machine, the combination of a plurality of slides capable only of rectilinear motion for printing the written part of a check, mechanism for moving said slides in straight lines to bring desired values into printing position, a plurality of

printing wheels for printing the numerical part of a check, devices connecting the slides and wheels for operation, and mechanism for setting the slides and wheels to the same amount by the same operation.

28. In a check writer, the combination of a set of ordered slides bearing characters for printing the written part of a check, a set of ordered printing wheels bearing characters for printing the numerical part of a check, gearing for actuating the printing wheels from the corresponding ones of the slides, one of said slides carrying two series of characters or words, one series belonging to one order and the other series including the same order and another order, and mechanism controlled by the operation of said slide for operating the wheel of the order corresponding to the first series when one of said series is brought into printing position and for controlling the operation of the same printing wheel and the printing wheel of another order when said slide is moved to bring one of said second series into printing position.

29. In a check writing machine, the combination of printing devices having digital indications in printing position, mechanism for setting said devices to print a desired amount, an actuating member for making a record from said devices, and mechanism for moving the digital indication of a printing device of higher value than the set up from printing position, and moving an arbitrary character of said device of higher value into printing position.

30. In a check writing machine, the combination of printing devices having digital indications in printing position, mechanism for setting said devices to print a desired amount, an actuating member for making a record from said devices, and mechanism for moving the digital indication of a printing device of higher value than the set up from printing position and locking a printing device involved in the set up amount in printing position.

31. In a check writing machine, the combination of printing devices having digital indications in printing position, mechanism for setting said devices to print a desired amount, an actuating member for making a record from said devices, and mechanism for moving the digital indication of a printing device of higher value than the set up from printing position, and locking devices actuated by said member for preventing a change in the set up amount during operation of said member.

32. In a check writing machine, the combination of printing devices having digital indications in printing position, mechanism for setting said devices to print a desired amount, an actuating member for making a record from said devices, and mechanism for

moving the digital indication of a printing device of higher value than the set up from printing position, and devices actuated by said member for retaining in printing position the digital indication of an unoperated printing device involved in the set up during operation of said member.

In witness whereof, I hereunto subscribe my name this 22 day of August, A. D., 1913.

EDMUND OCUMPAUGH.

Witnesses:

E. C. GECK,

I. STREB.
